UNITED STATES PATENT OFFICE.

ANKER PETERSEN, OF CHELSEA, MASSACHUSETTS.

CARRIER FOR BRAIDING AND SIMILAR MACHINES.

984,022.

Specification of Letters Patent. Patented Feb. 14, 1911.

Application filed July 15, 1907. Serial No. 383,717.

To all whom it may concern:

Be it known that I, ANKER PETERSEN, a subject of the King of Denmark, but at present a resident of Chelsea, in the county 5 of Suffolk and State of Massachusetts, have invented an Improvement in Carriers for Braiding and Similar Machines, of which the following description, in connection with the accompanying drawing, is a specification, like letters on the drawing representing like parts.

This invention relates to braiding machine carriers and has for its object to provide a carrier which is capable of sustaining 15 a very much larger thread mass than is commonly used in braiding machine carriers, and which does not make use of the dangling weights which are commonly employed in connection with the let-off mechanism of 20 such carriers. By dispensing with these weights and the parts for guiding the same, the total weight of the carrier is very much reduced, thus permitting the carrier to be run in the braiding machine at a very much 25 higher rate of speed.

The novel features wherein my invention resides will be hereinafter described and will then be pointed out in the appended claims.

30 Figure 1 in side elevation represents a carrier for a braiding machine, the same being represented as provided with the improvements made the subject of claims in this application, a portion of the bars B, 35 B' being broken away; Fig. 2 is a top or plan view of the carrier, the full lines showing the arms of the take-up and pull-off in operative position, the dotted lines showing the same in their normal positions, the 40 position they will occupy under the control of their springs; Fig. 3 shows the arms substantially in the position they will occupy preparatory to the release of the pawl forming part of the let-off; Fig. 4 is a section 45 below the dotted line 4, Fig. 1, and Fig. 5 is a section in the line 5—5, Fig. 4, below plate b.

The carrier shown has a base comprising 50 a bottom plate A and a foot A' connected by a neck A² that travels through the usual cross grooves of the braiding machine, the foot having a stud A³ shaped to be embraced by the notched driving arms or gears such as are usually employed in braiding machines as now made, for moving the carriers about in the carrier grooves. The bottom

plate A has connected with and rising therefrom suitable bars B, B' that in turn are connected at their upper ends with and sustain a top plate B². The top plate has a 60 central hole to receive the upper end of a spindle a, the lower end a' of which, see dotted lines Fig. 4, enters a hole a², see Fig. 5, made in a step a³ mounted on the upper side of the bottom plate. The spindle a' at 65 a short distance from its lower end is provided with a plate b shown as having a series of shoulders b' and notches b², and the spindle immediately above said plate, which is made as a ratchet toothed wheel, is provided with a portion b³ other than round, 70 said portion being preferably of the shape shown in Fig. 4, to be engaged by a notch made in the lower end of a small quill 2 preferably of wood, the upper end of which 75 is shown just above the thread mass C wound on said quill. The quill may be, in practice, about one-quarter of an inch in diameter, and the thread mass one and three-quarters of an inch, and preferably the 80 thread mass will be wound either on a Leeson winding machine, or in some other usual way to retain the thread in such form as to insure uniform unwinding.

On the top side of the bottom plate I pivot 85 a pawl d, using a screw d'. Said pawl has a shoulder which is acted upon normally by a spring d² connected with the bottom plate, and the end of the pawl is provided with an upturned lug 3 which is adapted to enter one 90 of a plurality of notches b² formed in the plate b. Said plate is also provided with shoulders b' which form continuations of one side of the notches. This pawl d forms part of a let-off mechanism which normally 95 locks the spindle and thread mass from turning but which is released from the spindle by an increased tension on the thread. When the pawl occupies the position shown in Fig. 1, it obviously will lock the plate b 100 and the spindle from turning. To effect the release of the pawl from the plate b when it is desired to let off more thread from the thread mass, I have provided the carrier with a rod or shaft d³ which is journaled in 105 the top and bottom plates respectively, and which has at its lower end an arm d⁶ adapted to engage a projection 12 carried by the pawl d. The shaft d³ is acted on normally by a spring d⁴ which tends to turn the shaft 110 in a direction to bring the arm d⁶ into the position shown in Fig. 4, that is, against one

of the bars B'. To accomplish this the spring d^4 may conveniently have its lower end fastened to the shaft d^3 while its upper end is bent to contact with the bar B'. The 5 portion of the rod or shaft d^3 above the upper plate B² is extended horizontally to form a let-off arm e' at the end of which is provided an eye e^2 . This eye is arranged to have the thread passed therethrough as will 10 be presently described, and when the tension on the thread is sufficient, the arm e' which normally occupies the dotted line position Fig. 2, is swung around into the position shown in full lines Figs. 2 and 3, and thus 15 turns the shaft d^3 thereby bringing the arm d^6 against the shoulder 12 and withdrawing the pawl from the notch in the plate b.

The take-up mechanism herein shown is in 20 the form of a take-up arm e^6 having an eye e^7 at its end, which arm is sustained by a rod or shaft e^4 that is journaled in the top and bottom plates B², A. The rod or shaft e^4 is surrounded by a spiral spring f, one end of which is made fast to the shaft by any suitable 25 means, and the other end of which is bent laterally to abut against the bar B. The take-up arm e^6 is arranged to stand at substantially right angles to the shaft e^4 and also stands parallel with the top plate B². 30 The spring f tends normally to turn the shaft e^4 into a position to carry the take-up arm e^6 into the dotted line position Fig. 2. The arm e^6 is provided with an eye e^5 in line with the axis of its movement. Said eye may 35 conveniently be formed by bending the wire constituting the shaft e^4 into proper shape to make the eye. The shaft e^4 is shown as having extending therefrom a projection f', which projection may conveniently be the 40 end of the spring f which surrounds said shaft. This projection f' is adapted to co-act with the bar B to act as a stop for limiting the swinging movement of the take-up arm in one direction.

45 The top plate b² has extending therefrom an arm presenting at its end a delivery eye g' and this eye is preferably made S-shaped so as to present two thread passages, as clearly seen in Fig. 1. The bar B' is also provided 50 with a thread guide g. When the carrier is properly threaded up and is in operation, the thread from the thread mass C is led through the thread guide g, thence into the lower passage of the delivery eye g', thence 55 into the eye e^2 of the let-off arm, thence around a pulley e which is rotatably sustained on the shaft d^3 , thence through the eye e^5 and through the eye e^7 at the end of the take-up arm, and thence through the 60 upper thread passage of the delivery eye to the cloth. When the thread is entirely free from tension, the take-up arm e^6 and the let-off arm e^8 will occupy the dotted line positions Fig. 2, but as the thread is subjected 65 to more or less tension, the take-up arm e^6 is

first drawn into the full line position Fig. 2 until it abuts against the delivery eye g' as a stop, and at the same time the let-off arm is drawn from the dotted line position toward the delivery eye. When the tension 70 increases sufficiently to turn the let-off arm into the position shown in Fig. 3, the pawl d will be released from the disk b and the spindle with its thread mass will be allowed to turn, thus giving up some thread. As 75 soon as the thread is given up, the spring d^4 tends to move the let-off arm into the position shown in Fig. 2, thus carrying the arm d^6 out of contact with the pawl and permitting the pawl to be brought up against the 80 next shoulder b', thus locking again the spindle and thread mass.

It will be observed that both the let-off arm and the take-up arm operate in planes parallel with the plate b² or in planes perpendicular to the thread mass. The advantage of this construction is that neither the take-up arm nor the let-off arm take up any appreciable amount of room and the presence of neither one of these arms increases 90 to any extent the size of the carrier. My invention also has the advantage that the take-up and let-off arms can be made comparatively light in weight and thus a braiding carrier capable of carrying a large quantity 95 of thread mass can be provided without making the braiding carrier so heavy that it cannot be run rapidly in the braiding machine.

Another advantage which is secured by 100 my improved construction is that derived from the fact that the thread passes around the pivotal point or axis of both the take-up arm and the let-off arm. By carrying the thread through the eye e^5 of the take-up arm, it will be seen that any movement of said 105 take-up arm will not produce any slack in or affect the thread between the eye e^5 and the roll e, such movement of the take-up arm affecting only the thread between the eye e^7 and the delivery eye g'. Similarly the movement 110 of the let-off arm does not affect the thread between the roll e and the take-up arm, but only affects the thread between the eye e^2 and the eye g'. The result of this 115 construction is that the two arms will accomplish their desired objects without interfering with each other.

Having fully described my invention, what I claim as new and desire to secure by Letters Patent is:—

1. In a braiding carrier, the combination with a carrier frame comprising rigidly-connected top and bottom plates, of means to sustain a thread mass between said plates, a delivery eye carried by the top plate, and a spring-controlled take-up arm movable in a plane parallel to the top plate.

2. In a braiding carrier, the combination with a carrier frame comprising rigidly-connected top and bottom plates, of a spindle

removably sustained by said plates, a delivery eye carried by the top plate, and a spring-controlled take-up arm situated above the top plate and movable in a plane parallel thereto.

3. In a braiding carrier, the combination with a carrier frame comprising rigidly-connected top and bottom plates, of a spindle removably sustained by said plates, a delivery eye carried by the top plate, and a pivoted spring-controlled take-up arm movable in a plane parallel to the top plate.

4. In a braiding carrier, the combination with a carrier frame comprising rigidly-connected top and bottom plates, of a spindle removably sustained by said plates, a delivery eye sustained by the top plate, a pivoted spring-controlled take-up arm movable toward and from the delivery eye in a plane perpendicular to the axis of the thread mass.

5. In a braiding carrier, the combination with a carrier frame comprising rigidly-connected top and bottom plates, of a spindle removably sustained by said plates, a delivery eye sustained by the top plate, a pivoted spring-controlled take-up arm situated above the top plate and movable toward and from the delivery eye in a plane perpendicular to the axis of the thread mass.

6. In a braiding carrier, the combination with a carrier frame comprising connected top and bottom plates, of a spindle extending between said plates, a rod or shaft journaled in said plates and extending parallel to the spindle, a take-up arm extending laterally from said rod or shaft, and a spring acting on said rod or shaft and tending to turn it in one direction.

40 7. In a braiding carrier, the combination with a carrier frame comprising connected top and bottom plates, of a spindle sustained by said plates, a rod or shaft journaled in the plates and extending parallel to the spindle, a take-up arm extending laterally from one end of said rod or shaft, said arm having an eye at its end, and another eye in line with its axis, and a spring acting on said rod or shaft tending to turn it in one direction.

50 8. In a braiding carrier, the combination with a carrier frame comprising means to sustain a thread mass, of a let-off mechanism, means controlled by the tension of the thread to operate said let-off mechanism, and a spring-controlled take-up arm acting on the thread, said take-up arm being independent from said last-named means.

55 9. In a braiding carrier, the combination with a carrier frame having means to sus-

tain a thread mass, of a let-off mechanism, 60 means controlled by the tension of the thread to operate said let-off mechanism, a delivery eye, and a spring-controlled take-up arm separate from the last-named means and acting on the thread between the let-off 65 mechanism and the delivery eye

10. In a braiding carrier, the combination with means to sustain a thread mass, of a lock acting normally to prevent the thread mass from rotating, means controlled by the 70 tension on the thread to release the lock, a delivery eye, and a spring-controlled take-up arm acting on the thread between said means and the delivery eye.

11. In a braiding carrier, the combination 75 with a carrier frame having means to sustain a thread mass, of means to lock the thread mass from turning, a spring-controlled let-off arm for releasing said lock, and a spring-controlled take-up arm sepa- 80 rate from the let-off arm.

12. In a braiding carrier, the combination with a carrier frame having connected top and bottom plates, of means to sustain a thread mass between said plates, means to 85 lock the thread mass from turning, a shaft journaled in said plates and provided at one end with a let-off arm movable in a plane parallel to the plates, and means operated by the shaft to release the lock.

90 13. In a braiding carrier, the combination with a carrier frame having means to sustain a thread mass, of a spring-controlled take-up arm pivoted to said carrier frame above the thread mass and provided with an 95 eye at its end and another eye in line with its axis, and a delivery eye sustained by said frame, the thread extending from the thread mass through the eye in line with the axis of the take-up arm and thence through the 100 eye at the end thereof to the delivery eye.

14. In a braiding carrier, the combination with a carrier frame comprising means to sustain a thread mass, of let-off mechanism controlled by the tension of the thread, and 105 a spring-controlled take-up arm separate from the let-off mechanism for operating said let-off mechanism, said take-up arm having an eye at its end and thread-guiding means in line with its axis.

110 In testimony whereof, I have signed my name to this specification, in the presence of two subscribing witnesses.

ANKER PETERSEN.
